UNITED STATES PATENT OFFICE.

JOHN HENRY LEPPER, OF MASON CITY, IOWA.

ELECTRICAL PRIMING-VAPORIZER.

1,297,369.

Specification of Letters Patent. Patented Mar. 18, 1919.

Application filed July 28, 1917. Serial No. 183,254.

To all whom it may concern:

Be it known that I, JOHN H. LEPPER, a citizen of the United States, residing at Mason City, in the county of Cerro Gordo and State of Iowa, have invented certain new and useful Improvements in Electrical Priming-Vaporizers; and I do hereby declare the following to be a full, clear, and exact description of the invention, such as will enable others skilled in the art to which it appertains to make and use the same.

This invention relates to new and useful improvements in electrical priming vaporizers for hydro-carbon motors, such as are used in automobiles.

The primary object of the invention is to provide means whereby such motors may be quickly and easily started, especially in cold weather, when the fuel is heavy and less volatile.

A further object of the invention is to connect a hydro-carbon reservoir embodying electrical vaporizing means to the carbureter and to the intake manifold whereby when the electrical means is energized, a sufficient supply of gas will be generated and admitted to the intake manifold to facilitate quick and ready starting of the motor.

With these and other objects in view as will appear as the description proceeds, the invention comprises the various novel features of construction, combination and arrangement of parts as will be fully described hereinafter and afterward specifically claimed.

Referring to the drawings,

Figure 1 represents a side elevation of the electrical priming vaporizer connected to the intake manifold and carbureter of a motor and the electrical circuit thereof, and

Fig. 2 represents a vertical sectional view through the vaporizer.

Similar characters of reference are used to denote corresponding parts throughout the accompanying drawings and the following description.

In order that the construction and operation of the invention may be readily comprehended, I have illustrated an approved embodiment thereof in the accompanying drawings and will now proceed to fully describe the same, in connection with said drawings, in which A indicates a hydro-carbon reservoir and comprises a glass or other transparent cylinder 1 closed at its upper end by a peripherally flanged top plate 2

and at its lower end by a similar flanged bottom plate 3, suitable gaskets 4 being interposed between the ends of the cylinder and plates to make leak proof joints.

5 indicates a vaporizing shell or chamber which has its upper end thickened and provided with a centrally threaded opening 6. The lower end 7 of the shell is threaded centrally through the bottom plate 3 so that the circumferential flange 8 rests firmly on the bottom plate to form a leak proof joint. The shell is provided adjacent the flange 8 with an opening 9 which establishes communication between the interior of the shell and the reservoir. The lower end 7 of the shell extends through a right angular bracket 10 and is secured thereto by a nut 11.

A plug 12 having a reduced upper end is threaded into the lower end of the shell and is provided centrally with a socket 13 for the reception of the lower end of a coil casing 14, said casing extending upwardly in the shell or vaporizing chamber and having its upper end 15 dome shaped. The coil casing may be held within the plug 12 on an insulating disk 16 in any suitable manner, such as by soldering or friction.

The cylindrical portion of the coil casing is lined with suitable insulating material 17 which extends up to the dome shaped end 15. A resistance or heating coil 18 is mounted within the casing 14 and has its lower end attached to the head of the bolt 19 extending through the plug 12 and disk 16, while the upper end of the coil is attached centrally to the dome end 15 in any suitable manner. 20 indicates an insulating sleeve surrounding the bolt 19, and 21 insulating washers which serve to insulate the bolt from the plug 12. The bolt is also provided with a lock nut 22 and a thumb nut 23.

An outlet pipe 24 extends centrally through the cover plate 2 and has its lower end threaded through the opening 6 in the shell 5 and terminates in close proximity to the dome end 15 of the coil casing. The upper end of the outlet pipe is integral with a cross head 25 having a restricted outlet passage 26 in one end, said passage being provided at its juncture with the outlet pipe 24 with a valve seat 27. A valve stem 28 is threaded through the other end of the cross head and has its outer end connected to an actuating rod 29 which is intended to extend through the automobile dash, in this instance, and be provided with an indicator

handle to indicate when the valve is open or closed. By screwing the outlet pipe 24 through the shell 5, the top and bottom plates 2 and 3 are securely clamped over the 5 ends of the cylinder 1 by virtue of the shoulder 80 on the outlet pipe.

In order to manually fill the fuel reservoir A, when desired a pet cock 31 is threaded through the top plate 2. The normal 10 supply of fuel for reservoir A is automatically fed by the suction force of the engine through a stand pipe 32 which extends upwardly from the bottom plate 3 and terminates in a plane substantially with the 15 top of the vaporizing chamber 5 said stand pipe serving as an over flow pipe when the device is not in operation to maintain a predetermined fuel level in the reservoir. This stand pipe 32 communicates with a threaded 20 nipple 33 projecting downwardly from the bottom plate, said nipple being connected to supply pipe 34 by a union 35. The other end of the over flow pipe 34 is connected to the nipple 36 of the carbureter 37 by a 25 union 38. 39 represents the engine intake manifold and is connected to the carbureter 37 in the usual and well known manner. An outlet pipe 40 has one end connected to the cross head 25 and its opposite 30 end connected to the intake manifold in any suitable manner found most desirable for the purpose intended. 41 represents a battery or other suitable source of current connected in circuit with one end of a switch 35 42, the switch contact point 42' being connected by a wire 43 to the bolt 19. The other terminal of the battery 41 is connected by a wire 44 to and grounded on the carbureter 37. A dash lamp 45 is connected to 40 the switch contact 42' by a wire 46 and to and grounded on the intake manifold by a wire 47, and serves to indicate by its illumination when the switch 42 is closed.

In the operation of the apparatus the gasoline throttle lever is first moved to a closed 45 position on the steering wheel of the automobile, after which the switch 42 is closed whereupon current will flow from the battery 41 through the switch, wire 43, bolt 19, coil 18, coil casing 14, plug 12, end 7, plate 3, pipe 34, carbureter 37, and wire 44 back to the battery, thus energizing and heating the coil 18 sufficiently to vaporize the fuel 50 within the chamber 5. At the same time the switch 42 is closed the valve 28 is opened so as to permit the hydro-carbon vapor to be sucked through the outlet pipe 24, passage 26, and pipe 40 to the intake manifold under the suction force of the engine for 55 quick and easy starting of the engine. By first closing the engine throttle valve and opening valve 28, and then turning over the engine, a suction force will be created in the device sufficient to automatically draw fuel 60 from the carbureter bowl to the reservoir. 65

After the engine has been started, the valve 28 is closed and the switch 42 opened and the engine operated in the usual manner.

The lamp 45 is preferably colored red so that when it is illuminated it will readily 70 attract the attention of the operator and indicate that the circuit is closed.

I claim:

1. A fuel vaporizer comprising a reservoir, an outlet pipe leading from the upper 75 end of said reservoir, a vaporizing chamber extending into said reservoir from the bottom thereof, said chamber having an aperture adjacent its lower end establishing communication with the reservoir, electrical vaporizing means projecting into said vaporizing chamber, and an inlet pipe connected to the lower end of the reservoir. 80

2. A fuel vaporizer comprising a reservoir, a vaporizing chamber projecting into 85 said reservoir from the bottom thereof, and provided with an aperture adjacent the reservoir bottom establishing communication with the reservoir, a vaporizing medium projecting into said vaporizing chamber from 90 the bottom thereof, a fuel feed pipe for said reservoir, and an outlet pipe extending through the reservoir and into said vaporizing chamber.

3. A fuel vaporizer comprising a reservoir, a vaporizing chamber projecting into 95 said reservoir, and provided with an aperture adjacent one end establishing communication with the reservoir, a vaporizing medium projecting into said vaporizing chamber, a fuel feed pipe for said reservoir, an outlet pipe extending through the reservoir and into said vaporizing chamber, and a controlling valve for said outlet pipe. 100

4. A fuel vaporizer comprising a reservoir, a vaporizing chamber projecting upwardly into said reservoir and provided with an aperture adjacent its lower end and establishing communication with said reservoir, a vaporizing medium projecting upwardly into said vaporizing chamber, a fuel feed pipe connected to the reservoir, and an outlet pipe extending through the reservoir and top of the vaporizing chamber. 110

5. A fuel vaporizer comprising a reservoir, a vaporizing chamber projecting upwardly into the reservoir and having an aperture adjacent its lower end establishing communication with said reservoir, a stand pipe extending upwardly from the bottom 115 of the reservoir, a fuel feed pipe connected to said stand pipe, a heating medium projecting into said vaporizing chamber, and an outlet pipe extending through the top of the reservoir and vaporizing chamber. 120

6. A fuel vaporizer comprising a reservoir, a vaporizing chamber removably positioned within and through the bottom of the reservoir, said chamber having an aperture adjacent its lower end communicating 125

with the reservoir, a vaporizing medium removably positioned within said vaporizing chamber, a fuel feed pipe for said reservoir, and a valve controlled outlet pipe extending through the reservoir and into said vaporizing chamber.

5 In testimony whereof I have signed my

name to this specification in the presence of two subscribing witnesses.

JOHN HENRY LEPPER.
